His Attorney.

UNITED STATES PATENT OFFICE

2,020,097

MERCURY TURBINE CONDENSER
ARRANGEMENTLeonard R. Biggs, Schenectady, N. Y., assignor to
General Electric Company, a corporation of
New York

Application August 30, 1934, Serial No. 742,137

4 Claims. (CL 257—28)

The present invention relates to mercury turbine condenser arrangements, more specifically to the kind of arrangements in which the cooling fluid, such as water, is evaporated by the heat transferred thereto from the condensing mercury vapor.

The object of my invention is to provide an improved construction and arrangement of mercury turbine condenser arrangements whereby mercury vapor is effectively condensed and the heat content of the non-condensable gases such as air is reclaimed.

For a consideration of what I believe to be novel and my invention, attention is directed to the following description and the claims appended thereto in connection with the accompanying drawing.

In the drawing, Fig. 1 is an end view partly in section of a mercury turbine condenser arrangement embodying my invention, and Fig. 2 is a side view of Fig. 1 partly in section.

The arrangement comprises a mercury turbine 10, in the present instance shown as being of the double flow type. Mercury vapor is conducted to the turbine through an inlet conduit 11 and discharged from the turbine through exhaust conduits 12 and 13, which latter are connected to an outer casing or shell 14 of a condenser. The condenser in accordance with my invention is disposed below the mercury turbine, and the aforementioned outer shell 14 is shaped so that the exhaust vapor of the turbine flows through the shell in downward direction at substantially constant velocity.

As will be readily seen from Fig. 1, the horizontal cross-section of the space defined by the outer shell decreases gradually in downward direction. The rate of decrease to a certain extent depends upon the cooling arrangement disposed within the shell 14. Said cooling arrangement in accordance with my invention comprises a circulation type boiler. The boiler has three lower headers, an intermediate header 15 and outer headers 16 and 17 connected to the intermediate header 15. The boiler also includes upper headers or drums 18 and 19 connected to the lower headers by up-tubes 20 and down-tubes 21. The drums 18 and 19 are connected by a pressure equalizing conduit 22 and each drum has a discharge conduit 23 and 24 projecting through the outer shell 14 and united therewith by welds 25. During operation, a cooling medium or, from another viewpoint, a fluid to be evaporated, in the present instance water, is conducted to the intermediate lower header

15 by a conduit 26 having two branch portions 27 and 28. The water flows from the intermediate header 15 partly through up-tubes 20 into the upper headers or drums 18 and 19, and partly through the outer headers 16 and 17 and 5 other up-tubes 20 to said drums 18 and 19. During this upward flow, the fluid is heated and partly evaporated, the vapor being discharged from the drums through the conduits 23 and 24 respectively, whereas the liquid is recirculated 10 through the down-tubes 21, which latter, as indicated in the drawing, have a considerably larger cross-section than the up-tubes 20. The provision of a circulation type boiler effects rapid circulation of cooling medium and accordingly 15 effective condensation of mercury and vapor as well as effective evaporation of water. All the high pressure parts of the boiler with the exception of the discharge conduits 23 and 24 are totally enclosed in the outer shell of the condenser. This I consider an important feature 20 of my invention because it eliminates excessive non-uniform stresses of different parts of the condenser. In my arrangement, all parts are uniformly heated and relative expansion between 25 various parts thereby is reduced to a minimum.

In the lower side portions of the inner shell, that is, in the coolest region of the condensing space, I provide means for extracting non-condensables, in the present instance shown as two 30 tubular members 29 and 30. Each of these members is connected to an auxiliary condenser 31 and 32 respectively. Said auxiliary condensers comprise an outer shell 33 forming upper headers 34 and 35 and being provided with a dividing 35 wall 36. The headers 34 and 35 are connected by cooling tubes 37. The headers 34 of the auxiliary condensers are connected to the branched conduits 27 and 28 respectively, whereas the headers 35 are connected to inlet conduits 38 40 for conducting cooling medium, in the present instance water, to the auxiliary condenser. The extraction conduits 29 and 30 for removing non-condensables from the main condenser are connected to the outer casings 33. The casing 33 in 45 addition has a discharge conduit 39 for non-condensables and a discharge conduit 40 for mercury liquid separated from the non-condensables. The conduits 40 of the two auxiliary condensers are connected to a mercury discharge conduit 50 41 of the shell 14 of the main condenser.

During operation, cooling medium, in the present instance water, is conducted through the inlet conduits 38 of the auxiliary condenser, whence it flows from the header 35 through the cooling 55

tubes 37 into the header 34, to be discharged through the branched conduits 27 and 28 respectively and the conduit 26 to the lower intermediate header 15 of the boiler. With this arrangement the heat content of the non-condensables and the vapor discharged therewith into the auxiliary condenser or condensers is recovered. The non-condensables extracted by the extraction conduits 29 and 30 from the main condenser are conducted across the cooling tubes 37 of the auxiliary condensers whereby the mercury contained therein is condensed and discharged through the tubes 40 into the discharge conduit 41 of the condenser. The non-condensables, such as air, are discharged from the auxiliary condensers through the discharge conduits 39 which in well known manner may be connected to the suction inlet of a pump, not shown, for removing non-condensables.

20 In a preferred embodiment, as shown in Fig. 1, I provide two auxiliary condensers, one on each side of the main condenser which has the distinct advantage that one of the auxiliary condensers may be repaired during operation of the turbine and in addition provides for a more uniform flow of vapor in the main condenser.

What I claim as new and desire to secure by Letters Patent of the United States, is:

1. A condenser having an outer shell arranged for connection to a turbine exhaust conduit and shaped to cause the vapor exhausted from such turbine to flow at substantially constant velocity from the upper towards the lower portion of the condenser space, a circulation type boiler totally enclosed in and substantially independent of expansion of said shell, said boiler comprising upper and lower headers connected by up-tubes and down-tubes, and means for conducting cooling fluid to the lower header and discharging evaporated fluid from the upper header.
2. A mercury condenser having an outer shell arranged for connection to a turbine exhaust conduit and shaped to cause the vapor exhausted

from such turbine to flow at substantially constant velocity from the upper towards the lower portion of the condenser space, a circulation type boiler totally enclosed by said shell and comprising upper and lower headers connected by 5 up-tubes and down-tubes, and means for removing non-condensables from the condenser and reclaiming heat energy from the non-condensables comprising an extraction conduit for non-condensables disposed near the coolest region in 10 the condenser space, an auxiliary condenser connected to the extraction conduit and means for conducting cooling medium through the auxiliary condenser to said lower header to recover the heat content of the non-condensables. 15

3. A mercury condenser having an outer shell arranged for connection to a turbine exhaust conduit and including a circulation type boiler totally enclosed within the outer shell, means for removing non-condensables from the condenser 20 space comprising extraction conduits disposed near the coolest regions of said space, two independent auxiliary condensers connected to the extraction conduits, means for conducting cooling medium through the auxiliary condensers to 25 the boiler, and means for separately discharging non-condensables and mercury liquid from the auxiliary condensers.

4. In a mercury condenser arrangement, the combination of an outer shell having an opening 30 for receiving mercury vapor, a circulation type steam boiler comprising upper and lower headers connected by up-tubes and down-tubes, the boiler being totally enclosed within the shell, means for conducting make-up water to a lower 35 header of the boiler, means for removing non-condensables from the condenser space, and means for reclaiming heat energy from the removed non-condensables comprising the aforementioned means for conducting make-up water 40 to the boiler.

LEONARD R. BIGGS.
